UNITED STATES PATENT OFFICE.

HERBERT H. RAMTHUN, OF MILWAUKEE, WISCONSIN.

WATER-MOTOR.

1,242,862.

Specification of Letters Patent.

Patented Oct. 9, 1917.

Application filed August 2, 1915. Serial No. 43,228.

To all whom it may concern:

Be it known that I, HERBERT H. RAMTHUN, a citizen of the United States, residing at Milwaukee, in the county of Milwaukee and State of Wisconsin, have invented new and useful Improvements in Water-Motors, of which the following is a specification.

This invention relates to water motors and more particularly to the rotor construction, the principal object of the invention is to provide a water motor, the rotor of which can be accurately constructed at a small cost with the resultant decrease in cost of the water motor as a whole.

A further object of the invention is to form the blades with a centrally arranged rib arcuate shaped in cross section for deflecting the water emerging from the nozzle to opposite sides of the rotor.

The invention consists in the features of construction, combination, and arrangement of parts, hereinafter fully described and claimed, reference being had to the accompanying drawings, in which:

Figure 1 is a vertical section through the water motor.

Fig. 2 is a side elevation thereof.

The remaining figures are detail sections showing the blades as attached to the disk of the rotor.

Referring to the drawings, the numeral 1 designates a rectangular casing in which is centrally arranged a rotor 2 that comprises a disk 3 and a series of blades 4 attached to its periphery. Each blade has a longitudinal rib 4' upstruck from its body throughout the length of the working face thereof and standing at the transverse center of the same in line with the disk, so that water falling thereon is to an extent divided and caused to pass to the sides of the disk.

Secured to the top wall of the casing and projecting therethrough is a nozzle 5 having its outlet end 6 arranged tangentially to the periphery of the disk so that the energy of the water issuing from the nozzle will act in the proper direction upon the blade. This nozzle has a swivel connection 7 with a hose line 8 shown in this particular instance as making connection with a spigot.

The disk is provided in its edge with a series of notches substantially radial there-

to and opening through the periphery thereof as best seen at 15 in Fig. 3, and with these notches are engaged the inner ends of the blades 4, by inserting the inner ends of the ribs 4' thereof into said notches as also best seen in Fig. 3. Each blade is by preference dished longitudinally a little, and perhaps also dished a trifle transversely, although in this direction the dishing is so little that the blade may be said to be substantially flat excepting for the rib, and the upstruck rib is arched as best seen in Fig. 4. It is the inner end of this arched rib that is inserted into the notch, and as the crown of the arch curves longitudinally to conform with the dish of the blade, the notch will have a corresponding longitudinal curvature as best seen in Fig. 3. This specific detail of construction makes the connection between each blade and the disk a closer one than if the blade and its rib were perfectly straight and the slot was also straight. Furthermore, owing to the configuration of the rib, a portion of the inner surface of the walls of the latter embraces the sides of the disk for preventing lateral movement while the frictional engagement between the rib and the slot will prevent outward movement of the blade.

As the pressure of the water issuing from the nozzle acts at a tangent to the periphery of the disk, it will be seen that there is very little stress tending to dislocate the blades in a radial direction with the result that only the centrifugal force has to be taken care of.

Having described the invention what is claimed is:

In a water motor, the combination with a disk having cut through it at its periphery a series of substantially radial notches, of a series of blades each dished slightly throughout its length and having at its transverse center an upstruck rib whose arch is inserted in one of said notches, all portions of the blade on opposite sides of its rib being substantially flat transversely, for the purpose set forth.

In testimony whereof I affix my signature in presence of two witnesses.

HERBERT H. RAMTHUN.
